UNITED STATES PATENT OFFICE.

JOHN C. RAMSAY, OF BALTIMORE, MARYLAND.

OVEN ATTACHMENT.

1,398,152.

Specification of Letters Patent.

Patented Nov. 22, 1921.

Application filed September 27, 1920. Serial No. 413,112.

To all whom it may concern:

Be it known that I, JOHN C. RAMSAY, a citizen of the United States, residing at Baltimore, State of Maryland, have invented 5 certain new and useful Improvements in Oven Attachments; and I do declare the following to be a full, clear, and exact description of the invention, such as will enable others skilled in the art to which it appertains to make and use the same.

This invention relates to an improved attachment for ovens, it being especially designed for use in connection with the ovens of gas ranges, although it is not to be restricted to this particular use.

There are on the market many gas ranges and portable ovens for use on gas stoves, these portable ovens and ovens of gas ranges being ordinarily provided in their bottoms 20 with a centrally arranged opening beneath which the gas burner is arranged and from which it is spaced. This construction and arrangement is objectionable since air currents passing beneath the bottom of the 25 range or underneath the stove catch the flame from the burner and deflect it laterally beneath the bottom of the oven. In this way, much heat from the burner is wasted and a waste of gas is also brought about. 30 This condition of affairs places much additional and needless expense on the user of ranges and stoves of this construction, and because of the great loss of needed heat, much time is consumed in properly heating 35 the oven.

It is my intention to overcome the above circumstances by employing an attachment in the form of a sleeve which may be inserted downwardly through the opening in 40 the bottom of the oven to surround the burner so as to create an upward draft, whereby practically all of the heat will be driven into the oven and at the same time the unnecessary lateral deflection of the 45 flame beneath the bottom of the oven will be overcome.

Another object of the invention is to provide an attachment of the above mentioned type which is removable so that when used 50 with portable ovens, it may be withdrawn into the interior of the oven and inverted so that it will be entirely out of the way and will leave the bottom of such oven entirely flush, so that it may be placed on a flat surface.

A further object of the invention is to

provide an attachment of the above mentioned class which also includes a combined article supporting and flame spreader plate for insertion in the oven over the hole in 60 the bottom of the latter, this plate being advantageous because it becomes intensely heated during operation of the range and thus serves as a hot plate on which articles of food may be placed and kept warm. It 65 is also advantageous in that it is a separate and independent element, thus permitting it to be supported on one of the usual grids in the oven when it is not in use.

A further object of the invention is to provide an attachment of the above mentioned 70 class which includes the aforesaid sleeve, the latter being provided at its inner end with a flange which rests on the oven bottom to retain the sleeve in place; together with the 75 aforesaid combined article supporting and flame spreader plate which includes depending legs engageable with the periphery of the flange on the sleeve. Thus, the flange is given the additional function of preventing 80 accidental and undue movement of the plate.

Other objects and advantages of the invention will be apparent during the course of the following description.

In the accompanying drawings forming a 85 part of this specification and in which like numerals are employed to designate like parts throughout the same:

Figure 1 is an elevational view, partly in section of a conventional type of gas range 90 with my improved attachments applied thereto.

Fig. 2 is a detail perspective view of one of the parts of my improved attachment.

For the purpose of enabling persons who 95 read this specification to obtain a clear understanding of the same, I have illustrated my improved attachment as being used in connection with a conventional type of gas range. Referring to these parts thereof by 100 letters, it will be seen that the letter E indicates a conventional type of gas range including an oven structure having a central opening in its bottom, beneath which the burner 9 is located and from which it is 105 spaced. Range E is, of course, provided with ledges L and article supporting grids G slideable on these ledges.

My attachment, as before intimated, includes a cylindrical relatively long sleeve 1 110 which is designed to be extended downwardly through the opening in the bottom

of an oven so as to surround the burner and extend a considerable distance below this burner. This sleeve is provided on its inner end with a laterally directed flange 2 which rests on the bottom of the oven and serves to retain the sleeve in position. It is also provided in one side with a slot 3 which straddles the fuel supply pipe of the burner and assists in retaining it in position and 10 prevents rotation thereof. With this sleeve in place, it will be seen that air passing beneath the stove or range will be directed upwardly through the sleeve and will thus create a draft, which will in turn carry practically all of the heat from the flame into 15 the oven, causing the latter to become immediately heated and serving to superheat the air in the oven. My attachment also includes a combined article supporting and 20 flame spreading plate 4 which is designed to be placed in the oven over the opening in its bottom. This plate, if desirable, may be provided with supporting legs 5 to space it above the bottom of the oven and permit the 25 flame to pass around it. It is to be noted, as before indicated, that the legs 4 of the plate are in engagement with the periphery of the flange 2, thus giving the flange the additional function of serving to hold the 30 "hot plate" in place and prevent accidental displacement thereof, which might otherwise occur.

From the foregoing description, it will be seen that I have devised an extremely effective and advantageous attachment for portable ovens used on gas stoves and for use in ovens of gas ranges. The employment of the relatively long sleeve creates a draft which effectively carries the heat from 40 the flame into the oven and superheats the air in the latter and thus causes it to become properly heated in an extremely short time. Furthermore, this sleeve prevents the flame from being deflected laterally beneath the 45 bottom of the oven, which circumstances causes an unnecessary waste of fuel. Then again, the plate 4 serves to distribute the heat more evenly in the oven, can be used as a hot plate on which articles of food may 50 be supported and kept warm, or may be used as a substitute for one of the grids for sup-

porting articles while the latter are being cooked. When my attachment is used in connection with portable ovens, it will not interfere with the placement of such an 55 oven on a flat surface, because the sleeve may be withdrawn into the oven and inverted as shown in dotted lines in Fig. 1 so as to be entirely out of the way.

While I have shown and described my attachment as being used in connection with stoves employing gas as a fuel, I wish it to be understood that it may be equally well used with similar stoves and ranges employing other kinds of fuel. 60 65

It is thought that a careful consideration of the foregoing description taken in connection with the accompanying drawings, will enable persons skilled in the art to which this invention relates, to obtain a 70 clear understanding of the same, therefore, a more lengthy description is deemed unnecessary.

Since probably the best results may be obtained with the construction and arrangement of parts herein described and shown, and I take this construction and arrangement as the preferred embodiment of my invention. However, I wish it to be understood that changes, so long as they do not 75 80 depart from the scope of the subjoined claim, may be made in the shape, size, and arrangement of parts of the attachment.

I claim:

In combination, an oven having a centrally disposed opening in the bottom, a burner disposed beneath and spaced from the opening, a cylindrical sleeve extending downwardly through said opening and surrounding the burner, said sleeve having a lateral annular flange on its inner end resting on the bottom of the oven, retaining the sleeve in place, and a combined article-supporting and flame spreader plate arranged in the oven over the aforesaid opening, said plate including depending legs engaged with the periphery of said flange, the latter serving to prevent undue shifting or possible displacement of the plate. 85 90 95

In testimony whereof I have hereunto set my hand.

JOHN C. RAMSAY.
